INVENTOR

BY James Holoyne.

ATTORNEY

UNITED STATES PATENT OFFICE.

EDWARD A. BLAKE, OF CHICAGO, ILLINOIS.

ROLL-GUARD FOR ROUGHING-MACHINES.

SPECIFICATION forming part of Letters Patent No. 324,806, dated August 25, 1885.

Application filed March 7, 1885. (No model.)

To all whom it may concern:

Be it known that I, EDWARD A. BLAKE, of Chicago, in the county of Cook and State of Illinois, have invented certain new and useful

55

Improvements in Attachments for Roughing-Machines; and I do hereby declare that the following is a full, clear, and exact description of the invention, which will enable others skilled in the art to which it appertains to make and 10 use the same, reference being had to the accompanying drawings, and to letters of reference marked thereon, which form a part of this specification.

The object of my invention is to provide 15 guards for the feed-rollers of roughing-machines which effectually prevent the shavings from passing under the roller with the electro-type or stereotype plate, thereby injuring the same.

20 In the drawings, Figure 1 is a plan view of the rollers of a roughing-machine, showing the manner of connecting my invention thereto. Fig. 2 is a perspective view of the guard.

In the drawings, A A represent the feed-rollers arranged transversely over the bed-plate parallel to each other and journaled in the heads B of the vertically-reciprocating rods. The chisel reciprocates longitudinally back and forth between the rollers, as indicated 25 by x, and the arrow y indicates the direction of the bed-plate while the machine is at work.

In order to prevent the shavings and particles of metal from getting under the roller opposed to the motion of the bed after the path 30 of the chisel is passed, I surround said roller, preferably about two-thirds of its circumference, with a guard. This guard C is made of sheet metal, and is provided with the arms b b, extending from one end, and the extension e, 35 extending from the other. These arms b b extend parallel to each other, and are separated a distance corresponding to the diameter of the barrel of the screw D, which projects from the inner vertical surface of the head B.

40 In the extension e, in alignment and on the same vertical plane as the space between the arms b at the other end of the guard, is an eye, d, the circular opening at the end of which is of a diameter corresponding to the head of the 45 screw E, projecting from the head B, in a position corresponding to that of screw D. The

elongated opening extending horizontally from the circular opening of the eye corresponds in width to the diameter of the barrel of the screw E.

The distance from the screw D to screw E corresponds to the distance from the circular opening of the eye d in one end of the guard to the extremity of the arms b, extending from the other end of said guard. Thus, to secure 50 the guard in position, it is placed so that the head of screw E passes through the circular opening of eye d, and the extremities of arms b will strike or bear against the barrel of screw D. The guard is then moved longitudinally 55 in the direction of screw D, so that the barrels of screws D and E will occupy the space between arms b b and the elongated opening of eye d, respectively, the heads of said screws preventing the removal of the guard laterally. 60

In order to lock the said guard C in position, I pivot at or near its center of length, in or near the extremity of the extension e, a dog, G. This dog G has a recess in its under edge, so that as the dog is oscillated it will pass over 75 the head or barrel of screw E, and thus prevent any longitudinal motion of guard C.

If desired, the elongated portion of the eye d may have at its extremity a right-angular turn to it. In this event the eye d is placed 80 on a lower plane, so that when said guard C is moved longitudinally it will drop when the angular turn of the elongated portion of eye d reaches the screw E, and its lower edge be parallel and equidistant from the upper surface 85 of the bed-plate.

Other means than those hereinbefore described may be adopted to secure the guard in position without departing from the spirit of my invention, which is the protection of the 90 feed-rollers of a roughing-machine, so that particles and shavings of metal cannot get under them.

The inner vertical part of this guard C passes vertically downward until its lower edge is on 95 the same horizontal plane as the under surface of the roller. This construction is resorted to to brush off the particles of metal left on the work from the chisel, so that the plate or work being planed will not be injured in its passage 100 under said rollers. Instead, however, of the said guard extending down to the same plane

as the under surface of the rollers, it may fall short of it, and a brush or rubber apron extend from the said lower edge, which will perform the same function.

5 What I claim as new, and desire to secure by Letters Patent, is—

1. In a roughing-machine, the combination, with the bed having a longitudinal motion and the feed-rollers placed transversely over said bed, of the guard C, protecting said rollers from dirt and particles of metal.

2. In a roughing-machine, a guard, C, adapted to partly surround the feed-rollers, and having its inner side contiguous to the 15 path of the chisel vertical and extending downward to the same horizontal plane as under surface of said rollers.

3. In a roughing-machine, a guard, C, adapted to protect the feed-rollers, as set forth,

having arms b b extending from one end thereof, and having an extension, c, extending from the opposite end, which is provided with the eye d, in combination with the said feed-rollers, their bearings, and the screws D and E.

4. The combination, in a roughing-machine, 25 with the feed rollers, their bearings, and screws D and E, projecting laterally therefrom, of the guard C, having arms b b and extension c, having an eye, d, and the dog G, fulerumed to said extension and having a recess in its under 30 edge, substantially as set forth.

In testimony that I claim the foregoing as my own I hereunto affix my signature in presence of two witnesses.

EDWARD A. BLAKE.
